UNITED STATES PATENT OFFICE.

ZELTON D. BRUMBERG, OF IRENTON, OHIO.

DESIGN FOR A DISPLAY DEVICE.

Application filed April 16, 1927. Serial No. 21,620. Term of patent 14 years.

To all whom it may concern:

Be it known that I, ZELTON D. BRUMBERG, a citizen of the United States, and a resident of Ironton, in the county of Lawrence and State of Ohio, have invented a new, original, and ornamental Design for a Display Device, of which the following is a specification, reference being had to the accompanying drawing, forming part thereof.

Figure 1 is a side elevation of a display device, showing my new design.

Figure 2 is a front elevation of a display device, showing my new design.

I claim:

The ornamental design for a display device, as shown.

ZELTON D. BRUMBERG.
